UNITED STATES PATENT OFFICE

153,062

DESIGN FOR A SPACE HEATER CABINET

Montgomery Ferar and Carl W. Sundberg, Detroit, Mich., assignors to Prentiss-Wabers Products Company, Wisconsin Rapids, Wis., a corporation of Wisconsin

Application October 9, 1947, Serial No. 141,828

Term of patent 7 years

(Cl. D81—19)

To all whom it may concern:

Be it known that we, Montgomery Ferar and Carl W. Sundberg, both citizens of the United States, residing at Detroit, in the county of Wayne and State of Michigan, have invented a new, original, and ornamental Design for a Space Heater Cabinet, of which the following is a specification, reference being had to the accompanying drawing, forming part thereof.

The figure is a perspective view, looking toward the front and one side of the space heater cabinet, showing our new design. The remaining cabinet side, not shown, is the same in appearance as the cabinet side which is exposed in the drawing.

We claim:

The ornamental design for a space heater cabinet, as shown and described.

MONTGOMERY FERAR.
CARL W. SUNDBERG.
